UNITED STATES PATENT OFFICE.

HOLLY HALL AND JOHN THOMAS WRIGHT, OF SLOCOMB, ARKANSAS.

NUT-LOCK.

1,081,499.

Specification of Letters Patent.

Patented Dec. 16, 1913.

Application filed April 24, 1913. Serial No. 763,405.

To all whom it may concern:

Be it known that we, HOLLY HALL and JOHN THOMAS WRIGHT, citizens of the United States, residing at Slocumb, in the 5 county of Saline and State of Arkansas, have invented certain new and useful Improvements in Nut-Locks, of which the following is a specification.

The present invention relates to improvements in nut locks, and is designed especially for use in locking nuts on bolts which secure fish plates in rail joints for railroads.

The primary object of the invention is the provision of a simple, but efficient, locking means for the purpose which may be produced at comparatively slight expense, and which may be applied with facility to lock a nut on a bolt against dislodgment or turning.

20 The invention consists essentially in providing a single, integral, metallic piece, struck up to shape for embracing a nut, and fashioned with a locking tongue and bracing foot, as will be hereinafter described and claimed.

In the accompanying drawings we have illustrated one complete example of the physical embodiment of our invention constructed according to the best mode we have 30 so far devised for the practical application of the principles of the invention.

Figure 1 is a transverse section of a railroad rail with fish plates bolted thereto, and our nut lock applied to the nuts. Fig. 2 is 35 a side view of Fig. 1. Fig. 3 shows a nut in section and our locking device applied thereto. Fig. 4 is a perspective view of our locking device before its application to a nut.

40 In the preferred embodiment of our invention we employ a metallic, or sheet metal, integral blank, from which the locking device is stamped or cut. In fashioning the locking device it is provided with two sides 45 or wings 1, 1, rectangular in shape and adapted to lie flat against the sides of the nut. These wings or sides pieces are joined at the bottom by plate 2, from which extends an elongated tongue 3 formed with 50 a reduced end 3'. A vertical web 4 ex-

tends downward from the bottom plate 2 and at right angles thereto, and from this web is projected the foot brace 5.

In the drawings we have illustrated a joint between the two rail ends 6 and 7 55 which are secured by the bolts 8, 8, and nuts 9 the usual fish plate 10 being employed.

The nut locking device is applied after the nut has been screwed home. With the parts of the locking device bent as shown 60 in Fig. 4, the device is applied to the nut with the side wings 1, 1, embracing the sides of the nut, the bottom plate 2 at the underside, the web 4 lying flat against the vertical portion of the fish plate, and the foot 5 65 resting upon the flat portion of the fish plate. The tongue 3 is now bent on the line of its juncture with the bottom plate 2, upwardly, and the end is extended over the top of the nut 9. One side face of the nut 70 is provided with a slot 9' for the reception of the end of the tongue 3, and the end of the tongue is bent down and shoved into the slot. Or if necessary a hammer blow may be resorted to drive the tongue into 75 the slot. In actual practice all four sides of the nut may be provided with slots 9', as indicated in dotted lines Fig. 3, and any one of these four slots may receive the end of the tongue. When the tongue is inserted. 80 and frictionally held, in the slot 9' the nut is prevented from turning on the bolt, as it is securely locked by the tongue, and the side wings 1, 1, and bottom plate 2 also aid in holding the nut in place. The foot portion 85 5 prevents the bodily movement of the nut and locking device, and positively holds the parts against turning.

The material of the locking device may be flexible or malleable, but in any event will 90 be tempered to a condition suitable for the purpose for which the device is intended.

From the above description taken in connection with the drawings it is believed the meritorious features and advantages of the 95 present invention will be evident, and a device has been described which will fulfil the objects set forth as the purpose of the invention.

Having thus fully described our inven- 100

tion, what we claim as new and desire to secure by Letters Patent is:—

1. The combination with a bolt and slotted nut of a locking device comprising an integral member embracing the nut and provided with a brace, and a flexible tongue having its end inserted in the slot of the nut.
2. The combination with a bolt and slotted nut and a fish plate of a rail joint, of a locking device having side wings and a bottom plate engaging the nut and a web

and foot brace engaging the fish plate, and a flexible tongue properly bent and having its end inserted in the slot of the nut.

In testimony whereof we affix our signatures in presence of two witnesses.

HOLLY HALL.
JOHN THOMAS WRIGHT.
